CLAIM

The ornamental design for a eyeglass arm as shown and described.

DESCRIPTION

FIG. 1 is a front perspective view of a eyeglass arm showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view taken from portion 8 of FIG. 1; and,

FIG. 9 is an enlarged detail view taken from portion 9 of FIG. 1.

The dot-dash broken lines depict the boundary of the enlarged views and form no part of the claimed design.
